UNITED STATES PATENT OFFICE.

ANKER PETERSEN, OF WINTHROP, MASSACHUSETTS.

BRAIDING DIE.

Application filed August 16, 1922. Serial No. 582,165.

To all whom it may concern:

Be it known that I, ANKER PETERSEN, a citizen of the United States of America, and resident of Winthrop, in the county of Suffolk and State of Massachusetts, have invented new and useful Improvements in Braiding Dies, of which the following is a specification.

The present invention concerns braiding machines of that type employed in the manufacture of braided cord or thread and relates more particularly to means for ensuring uniformity of tension in the strands of the finished braid.

15 The principal object of the present invention is to provide an improved form of braiding die or condenser, comprising means for retarding or holding back any slack portion or bight of a strand or strands as they are intertwined at the braiding point, thus to ensure substantially uniform tension in each strand of the finished braid as the latter is drawn off by the take-up device, but so constructed and arranged as to permit the 20 passage of knots or slubs without putting undue strain upon the strands, and to provide means whereby the die or condenser may be heated if desired for imparting a 25 set to the strands comprising the braid and 30 for giving a finished appearance to the latter.

In the accompanying drawings a preferred embodiment of the invention is illustrated and in such drawings;—

35 Fig. 1 is a fragmentary side elevation of a braiding machine of well known type and such as is shown in the patent to Petersen, No. 1,413,773, dated April 25, 1922, the device of the present invention being shown as 40 applied thereto;

Fig. 2 is a fragmentary horizontal cross section on the line 2—2 of Fig. 1 and indicating the position of the braiding die forming the subject-matter of the present application;

45 Fig. 3 is a vertical diametral cross section to large scale showing the improved braiding die;

Fig. 4 is a transverse cross section on the 50 line 4—4 of Fig. 3;

Fig. 5 is a perspective view of the braid compressing blade constituting an essential feature of the improved die;

Fig. 6 is a perspective view of a spring 55 employed for actuating the blade shown in Fig. 5;

Fig. 7 is a fragmentary, transverse cross section through the braiding die to larger scale showing the form of the inner edge of the blade; and

60 Fig. 8 is a fragmentary diametral cross section illustrating the lower part of the braiding die on an enlarged scale and indicating the position of the braiding point and of the braid as it passes through the 65 die.

Referring to the drawings the numeral 1 indicates the circular frame of the machine supported upon legs 2 and having the circular disk-like support 3 constituting a track 70 along which the braiding carriers 4 (Fig. 2) of the inner series may travel. The numeral 5 indicates the support for the outer series of braiding carriers 6. An upper frame 7 is provided which bridges the machine and has a bracket 8 in which the upper 75 end of the braiding die may be clamped. This upper frame also supports the take-up wheel 9 which may be driven in any suitable manner and which may be provided with a 80 counting mechanism 10 if desired.

Referring more particularly to Figs. 3 to 8, the improved die is shown as comprising a substantially cylindrical elongate member 11 having an axial bore or passage 12 85 through which the braid may travel. A radial slot 13 extends outwardly from one side of this passage to the exterior of the member 11. This slot is somewhat narrower at its inner portion and has a movable blade 90 14 fitting within such narrow portion. This blade is of substantially the same length as the member 11 and is grooved at its inner edge to provide an arcuate surface 15 constituting a portion of the side wall of the 95 passage 12. The upper end of the blade 14 is preferably made somewhat wider than the remainder as indicated at 16 (Figs. 3 and 5) while the lower end of the blade is chamfered off at 17 to facilitate the movement 100 of the blade as will hereinafter be described. Preferably also the lower end of the channel or groove 15 is flared outwardly as shown at 18 (Fig. 8) to facilitate the entrance of the braid. At a point intermediate its length, 105 and preferably above its central point, the blade 14 is provided with a hump or projection 19 upon its outer edge. A laminated leaf spring 20 of bow form is seated within the outer and widened portion 21 of the slot 13. This spring bears against the projection 19 at a point intermediate its ends and

110

2
has its opposite extremities 22, 23 respectively, bearing against the inner walls of a pair of caps 24, 25 fitting snugly over the upper and lower ends respectively of the member 11. These caps thus serve to retain the spring 20 within the slot and indirectly to prevent escape of the blade 14 from the slot. The cap 24 is provided at its end with an opening 26 for the passage of the braid, 10 this opening aligning with the passage 12 in the member 11. The lower cap 25 is provided with a beveled end surface 27 and has an opening 28 in its end aligning with the passage 12 in the member 11. The beveled 15 face 27 of the cap 25 serves to guide the strands toward the opening 28 which constitutes the braiding point.

In Figs. 2 and 8 the strands 29 are indicated as meeting at the point 28 and being 20 intertwined to form the braid B. As ordinarily constructed each braiding carrier is provided with means for tensioning its thread but as it is almost impossible to maintain absolutely uniform tension upon 25 each of the large number of strands meeting at the braiding point, it is found that in braids as ordinarily formed certain strands fail to bear their due proportion of any strain to which the finished braid may 30 be subjected. By the employment of the present device each strand as it arrives at the braiding point is retarded in its movement by reason of the pressure of the blade 14 against the braid, this pressure serving 35 to hold back any strand which may be slack, so that as the several strands emerge from the braiding die in the finished braid they all have substantially the same tension. If 40 the strands were always perfectly smooth, of the same diameter, and free from knots or slubs, it might be possible to secure the desired result by passing the braid as it leaves the braiding point through a restricted channel or passage having immovable side walls but as knots or slubs are 45 frequently incorporated in the strands such an arrangement would quickly result in the breaking of the braid or of individual strands and thus the movable blade has been 50 provided with the spring for resiliently pressing it against the braid. It is desirable however, that such blade be subjected to considerable pressure in order to secure the desired results and to permit of such 55 pressure while at the same time to allow the blade to move outwardly under the impact of a knot or slub, it is preferred to cause the spring to bear upon the blade at a single point so that the blade is free to 60 rock about this point as a fulcrum as the knot or slub traverses the passage 12, and it is further preferred to arrange the fulcrum point nearer to that end of the die 65 from which the braid emerges than to the lower end or braiding point. With such

an arrangement the entering slub or knot acts with a long leverage to swing the blade outwardly, thus avoiding any sudden strain upon the individual strand and permitting the knot or slub gradually to be compressed 70 as the braid traverses the passage 12 so that by the time it reaches the fulcrum point there is little danger of subjecting the strand to sufficient strain to cause its breakage. In order to facilitate the swinging 75 of the blade the lower end thereof is chamfered off as shown at 17 while the flaring entrance 18 to the channel 15 serves to avoid any retention of knots or slubs at the 80 entering point.

In Fig. 1 a heating coil 30 is shown as surrounding the cylindrical member 11, this heating coil comprising a plurality of turns of insulated electric wire mounted 85 between the heads 31 and 32. These heads are preferably positioned by engagement with the inner ends of the caps 24, 25 respectively. Lead wires 33, 34 extend from the coil and may be connected with any suitable source of electrical energy. By 90 the use of a heating coil at this point the strands forming the braid may be given a permanent set so that they tend to retain their relative positions in the braid, thus 95 producing a braid or yarn of improved appearance. The heating of the die in this manner is of particular advantage when one or more of the strands forming the braid are caused to pass through a sizing 100 bath or other conditioning medium prior to incorporation in the braid, as in this case the heated die may be caused to produce a glossy finish upon the braid adding very materially to its appearance and its desirability as a sewing thread. While an electric heating coil is herein disclosed it is evident that a steam coil or in fact any other desired heating means might be employed 105 for the purpose.

What I claim and desire to secure by Letters Patent of the United States is:

1. A braiding die comprising an elongate member having an axial opening for the passage of the braid, a bodily movable element constituting one side wall of said opening, and resilient means reacting against said element at a single point disposed substantially nearer to one end thereof than the other.

2. A braiding die comprising an elongate member having a longitudinally extending opening for the passage of the braid, a bodily movable element constituting one side wall of said opening, and a spring bearing against said element at a point substantially nearer to that end of the die at which the braid leaves it than to the other end thereof.

3. A braiding die comprising an elongate cylindrical member having an axial

- passage for the braid, an elongate radial slot leading inwardly to said passage, a bodily movable member seated within said slot and constituting a portion of the side 5 wall of said passage, and a spring bearing against said member at a point substantially nearer one end thereof than the other and tending to move said member radially inward.
10. 4. A braiding die comprising a cylindrical member having an axial passage for the braid and a radial slot leading into said passage, an elongate blade within said slot, means engageable with opposite ends of 70 said blade for preventing its escape from the slot, and a spring bearing against the outer edge of said blade at a point nearer to one end thereof than to the other.
5. A braiding die comprising an elongate 20 member having a longitudinal passage for the braid, a movable blade having an edge constituting a portion of the side wall of said passage, and a leaf spring of bow form having an intermediate portion thereof bearing 75 against said blade at a point nearer one end thereof than the other, and means for positioning the opposite extremities of said spring.
6. A braiding die comprising a cylindrical 30 member having an axial passage and a radial slot merging into said passage and extending from end to end of said member, a blade fitting within said slot and having an arcuate inner edge constituting a portion 80 of the wall of said passage, said blade having a projection upon its outer edge, and a spring bearing against said projection for bodily moving said blade radially inward.
7. A braiding die comprising a member 40 having an elongate passage for braid, a blade extending longitudinally of said passage, and resilient means reacting against said blade for urging it bodily in a radial direction to restrict the passage, the parts being so constructed and arranged that the 85 blade may rock freely for permitting the free passage of knots or slubs in the braid.
8. A braiding die comprising a member 50 having a passage for the braid, an elongate blade having an edge constituting a part of the side wall of said passage, and a spring bearing at a single point intermediate the 90 length of such blade and urging it in a direction to compress the braid, the point of engagement of the spring with the blade constituting a fulcrum about which the blade may freely swing to facilitate the passage 95 of knots or slubs in the braid.
9. A braiding die comprising a member 60 having an elongate passage for the braid, a blade having an edge constituting one side wall of said passage, and having a projection upon its opposite edge, said projection being nearer that end of the die at which the 100 braid leaves than to the end at which it enters, and a leaf spring bearing upon said projection, the latter constituting a fulcrum about which the blade is free to swing to facilitate the passage of enlargements in the braid.
10. A braiding die comprising a cylindrical member having an axial passage for the braid and a radial slot leading into said 105 passage, an elongate blade seated in said slot, means engageable with opposite ends of said blade to prevent its escape from the slot, said blade having a projection upon its outer edge disposed nearer that end of the die at which the braid leaves than to the other, and a bow spring having its opposite ends bearing against said blade retaining means and an intermediate portion thereof bearing against said projection.
11. A braiding die comprising a member having a passage for braid and an elongate 110 slot communicating with said passage, a bodily movable blade fitting within said slot, and a spring urging said blade inwardly toward the passage, the reaction of the spring against the blade being less effective at that part of the blade which lies adjacent to the end of the die at which the braid enters than at the other end.
12. A braiding die comprising a cylindrical member having an axial passage for 115 braid and a radial slot communicating with said passage, a blade fitting within said slot and extending longitudinally thereof, an apertured cap fitting over each end of said member and respectively overlapping the opposite ends of the blade to prevent its escape from the slot, the aperture on one of said caps determining the braiding point, and a bow spring having its opposite ends seated beneath the edges of the respective 120 caps and having an intermediate portion thereof bearing against said blade at a point nearer to that end of the die which is remote from the braiding point than to the other end thereof.
13. A braiding die having a restricted 125 passage for the braid, and means for heating said die whereby to impart a set to the strands forming the braid.
14. A braiding die having a restricted 130 passage for the braid, and a heating coil surrounding said die for heating it.
15. A braiding die comprising a cylindrical member having an axial passage for the braid, a resiliently actuated element associated with said passage for compressing the braid as it passes therethrough, a cap fitting over each end of said member and constituting retaining means for said element, and an electrical heating coil surrounding said 135 cylindrical member and positioned between said caps.
16. A braiding die comprising a cylindrical member having an axial passage for the braid and a radial slot leading into said 140

passage, a blade fitting within the slot and having an inner, channeled edge constituting one side wall of the passage, a spring bearing against the outer edge of said blade, a heating coil surrounding said cylindrical member, and a pair of caps fitting over opposite ends of said member and serving

to retain said blade and spring in operative position, and to position the heating coil, one of said caps defining the breaking point. ¹⁰
Signed by me at Boston, Massachusetts,
this ninth day of August, 1922.

ANKER PETERSEN.

Certificate of Correction.

It is hereby certified that in Letters Patent No. 1,469,530, granted October 2, 1923, upon the application of Anker Petersen, of Winthrop, Massachusetts, for an improvement in "Braiding Dies," an error appears in the printed specification requiring correction as follows: Page 4, line 10, claim 16, for the word "breaking" read *braiding*; and that the said Letters Patent should be read with this correction therein that the same may conform to the record of the case in the Patent Office.

Signed and sealed this 4th day of December, A. D., 1923.

[SEAL.]

KARL FENNING,
Acting Commissioner of Patents.
